COLLAPSIBLE ASH TRAY OR SIMILAR ARTICLE

Menefee Roots, Arlington, Tex.

Application May 10, 1955, Serial No. 35,905

Term of patent 14 years

(Cl. D85—2)

Fig. I

Fig. II

Fig. III

Fig. IV

Fig. V

Fig. I is a top perspective view of a collapsible ash tray or similar article, showing my new design;

Fig. II is a top plan view of the collapsible ash tray or similar article;

Fig. III is an end elevational view of the collapsible ash tray or similar article;

Fig. IV is a bottom plan view of the collapsible ash tray or similar article; and

Fig. V is a perspective view showing the collapsible ash tray or similar article in collapsed condition.

I claim:

The ornamental design for a collapsible ash tray or similar article, as shown.
